ABSTRACT OF THE DISCLOSURE

There is provided a process for the production of an N:N'-disubstituted 4:4'-bipyridylum salts by the interaction of an N:N'-disubstituted tetrahydro-4:4'-bipyridyl with a carbon compound containing a labile halogen atom wherein the labile halogen atom is attached to carbon by a bond of dissociation energy less than about 70 kcal./mole. The process will produce salts which are useful as herbicides.

This invention relates to the production of bipyridylum salts and particularly to the production of bis-quaternary salts of 4:4'-bipyridyl.

It is known that bis-quaternary salts of 4:4'-bipyridyl are useful herbicides and these compounds are usually made by a quaternisation reaction from 4:4'-bipyridyl. It is also known that N:N'-dibenzyl tetrahydrobipyridyl can be oxidised to an N:N'-dibenzyl bipyridylum salt by the action of iodine, but this process gives only poor yields of the bipyridylum salt, and much of the starting material is converted into benzyl pyridinium salts by fission of the bond connecting the two pyridine rings.

In U.K. applications Nos. 14,720/64 and 36,729/64, certified copy of which is in the file of U.S. application Ser. No. 445,770, filed on Apr. 5, 1965, we have described processes whereby N:N'-disubstituted tetrahydro-4:4'-bipyridyls may be oxidised to N:N'-disubstituted-4:4'-bipyridylum salts by organic oxidants particularly quinones. We have now found that the N:N'-disubstituted-tetrahydro-4:4'-bipyridyls may be converted in good yield into N:N'-disubstituted 4:4'-bipyridylum salts by the action of compounds containing a labile halogen atom.

Thus according to our invention we provide a process for the conversion N:N'-disubstituted tetrahydro-4:4'-bipyridyls to N:N'-disubstituted - 4:4' - bipyridylum salts which comprises treating the tetrahydrobipyridyl with one or more carbon compounds which each contains a labile halogen atom. We do not include fluorine in the term "halogen atom."

The tetrahydrobipyridyls which may conveniently be used in our process are those more fully described in the above mentioned U.K. applications, for example tetrahydrobipyridyls which carry alkyl or carbamyl alkyl, and particularly methyl or N:N'-disubstituted carbamyl methyl substituents on the nitrogen atoms. Other suitable N:N'-disubstituted-tetrahydro-4:4' - bipyridyls are those carrying inert substituents, for example alkyl groups, on the carbon atoms of the pyridine nuclei.

The carbon compound containing a labile halogen atom may be any such compound which is capable of

2

removing hydrogen from the tetrahydrobipyridyl, for example a compound containing a carbon-to-halogen bond of dissociation energy less than about 70 kcals./mole. Such carbon compounds include those in which the halogen is attached to an electron withdrawing group for example a —CH₂Hal₃ (where Hal=Cl, Br or I), —CO, —F, —Br or —Cl group. We have found that it is convenient to use liquid or solid carbon compounds and particularly liquid or solid compounds containing less than 4 carbon atoms per molecule. Bromine and iodine atoms tend to be more labile than chlorine atoms when attached to carbon and compounds containing bromine and iodine will therefore tend to be more effective than those containing chlorine only. However compounds containing bromine and iodine are relatively expensive and it is therefore economically desirable to use the cheaper compounds containing chlorine. We also prefer to use highly halogenated compounds and in particular fully halogenated compounds such as carbon tetrahalides (other than carbon tetrafluoride). In particular there may be used a carbon tetrahalide which does not contain fluorine, for example carbon tetrachloride, carbon tetrabromide, bromotrichloromethane or dichlorodibromo m e t h a n e. Other compounds which may be used in our invention are bromoform, iodoform, methylene iodide, hexachloroethane, hexachloropropene, 1:1:1 - trifluoro - 2:2 - dibromo-2-chloroethane and hexachloroacetone. We have found that use of chloroform, methylene dichloride, benzotrichloride and monochlorobenzene tends to yield very little of the desired product.

The tetrahydrobipyridyl and the carbon compound containing the labile halogen atom may be interacted simply by mixing the two components, but this procedure tends to give rise to a vigorous reaction which may be difficult to control. We have therefore found it useful to moderate this reaction by carrying it out in solution in an inert solvent. Suitable solvents are those which will dissolve the N:N'-disubstituted-tetrahydro-4:4'-bipyridyl and also the carbon compound containing the labile halogen atom. Examples of such solvents are ethers for example diethyl ether, tetrahydrofuran, 1:2 - dimethoxyethane, bis - (2-methoxyethyl) ether and 1:4-dioxane; ketones, for example acetone; hydrocarbons, for example benzene and hexane; organic bases, for example pyridine; halogenated hydrocarbons, other than those used to interact with the tetrahydrobipyridyl, particularly chlorinated hydrocarbons, for example chlorobenzene, chloroform and methylene dichloride; amides, particularly tertiary alkyl-amides, for example formamide; sulphoxides, for example dimethyl sulphoxide or nitriles, for example acetonitrile. We prefer that the tetrahydrobipyridyl and the carbon compound containing a labile halogen atom be dissolved in the same solvent as this avoids difficulties inherent in the use of mixed solvents.

The concentration of the tetrahydrobipyridyl may conveniently be above about 0.75 mole per litre and the concentration of the carbon compound containing a labile halogen atom, for example carbon tetrachloride, may be above about 0.25 mole per litre. Lower concentrations of either reagent necessitates the recovery of the N:N'-disubstituted bipyridylum salts from large quantities of solvent and therefore tend to be inconvenient. Either reagent may if desired be used undiluted, the other reagent being dissolved in the chosen solvent, but if the reagents are

used in high concentration care should be taken that the reaction does not become too vigorous and lead to some destruction of the desired product or to the production of unwanted by-products.

We prefer to use such a proportion of carbon com-

halogen atom, the solvent, the concentration of the reagents in the solvent, the reaction temperature and the time of the reaction. These variations and their effects on the yield of bipyridylum salts calculated on the tetrahydrobipyridyl used are set out in the following table.

TABLE

Carbon Compound (A) containing a labile halogen atom	Weight of (A) gms.	Solvent	Volume of (A) solution, ml.	Volume of tetrahydrobipyridyl solution, ml.	Temperature, °C.	Reaction time, hrs.	Yield of bipyridylum salt, per cent of theory

pound containing a labile halogen atom that two labile halogen atoms are available for each molecule of tetrahydrobipyridyl; thus about, or rather more than, 2 moles of a carbon compound containing one labile halogen atom per molecule should be used to interact with 1 mole of tetrahydrobipyridyl. A smaller proportion of carbon compound containing a labile halogen atom will tend to leave some of the tetrahydrobipyridyl unreacted and a larger proportion will leave an excess of the halogen containing carbon compound.

The temperature at which reaction is carried out will depend on the concentration of the reagents and on the particular reagents used. We have found that suitable temperatures are from about -55° C. to 70° C. and preferably from 0° C. to 50° C.; higher temperatures tend to cause decomposition of the tetrahydrobipyridyls and lower temperatures will necessitate cooling of the reagents. The most suitable time of reaction can be found by simple experiment and will depend on the reagents used and the temperature at which the reaction is carried out; we have however found that a minimum time of 20 to 30 minutes is generally necessary. The mechanism of the reaction is at present obscure but it appears that the labile halogen atom from the carbon compound is replaced by one of the hydrogen atoms from the tetrahydrobipyridyl. Thus when carbon tetrachloride is used in the reaction chloroform as well as the N:N'-disubstituted bipyridylum salt is found in the reaction product.

The N:N'-disubstituted bipyridylum salt may be recovered from the reaction mixture by conventional processes for example by extraction of the reaction mixture with water or with a dilute aqueous solution of a mineral acid such as sulphuric, hydrochloric or phosphoric acid. The N:N'-bipyridylum salt may then be recovered from the aqueous phase, which has previously been separated from the organic phase, by evaporation of the water and crystallisation of the salt.

The invention is illustrated but not limited by the following example in which the parts and percentages are by weight.

EXAMPLE

A solution of 1:1 - dimethyl-1:1':4:4'-tetrahydrobipyridyl (16.55 gms.) in an inert solvent was mixed with a solution of a carbon compound containing a labile halogen atom in the same solvent. The mixture was heated to the required temperature and maintained at the temperature for a given time. The mixture was then treated with aqueous hydrochloric acid (7.3 gms. in 200 mls.), and the aqueous phase separated and analysed polarographically for N:N'-dimethyl-4:4'-dipyridylum salts. The procedure set out above was repeated, variations being made in the carbon compound containing a labile

halogen atom.

25 1. A process for the production of an N:N'-dilower alkyl-4:4'-bipyridylum salt which comprises reacting in an inert solvent a N:N'-dilower alkyl tetrahydro-4:4'-bipyridyl with a linear alkyl or linear alkenyl carbon compound having less than 4 carbon atoms and containing a labile halogen atom selected from chlorine, bromine and iodine and the labile halogen atom is attached to carbon by a bond of dissociation energy less than about 70 kcal./mole.

30 2. A process as claimed in claim 1 wherein the labile halogen atom is attached to a carbon atom which is attached to an electron withdrawing group.

35 3. A process as claimed in claim 2 wherein the electron withdrawing group is a carbonyl group, a $-\text{CHal}_3$ group (where Hal represents chlorine, bromine or iodine), or a fluorine, chlorine or bromine atom.

40 4. A process as claimed in claim 1 wherein the labile halogen atom is chlorine.

5. A process as claimed in claim 1 wherein the carbon compound is fully halogenated.

6. A process as claimed in claim 1 wherein the carbon compound is a carbon tetrahalide not containing fluorine.

7. A process as claimed in claim 6 wherein the carbon tetrahalide is carbon tetrachloride or carbon tetrabromide.

8. A process as claimed in claim 1 wherein the carbon compound is bromotrichloromethane, dichlorodibromo-methane, bromoform, iododform, methylene iodide, hexachloropropene, hexachloroacetone or 1:1:1-trifluoro-2:2-dibromo-2-chloroethane.

9. A process as claimed in claim 1 wherein the interaction of the tetrahydrobipyridyl and the carbon compound containing a labile halogen atom is carried out in an inert solvent.

10. A process as claimed in claim 9 wherein the solvent comprises an ether.

11. A process as claimed in claim 10 wherein the ether is diethyl ether, tetrahydrofuran or bis-(2-methoxy ethyl) ether.

12. A process as claimed in claim 9 wherein the solvent comprises diethyl ether, tetrahydrofuran, 1:2-dimethoxyethane, bis-(2-methoxyethyl) ether, 1:4-dioxane, acetone, benzene, hexane, pyridine, chlorobenzene, chloroform, methylene dichloride, formamide, dimethyl sulphoxide and acetonitrile.

13. A process as claimed in claim 9 wherein the initial concentration of tetrahydrobipyridyl in the reaction mixture is more than about 0.75 mole per litre.

14. A process as claimed in claim 9 wherein the initial concentration of carbon compound in the reaction mixture is more than about 0.25 mole per litre.

15. A process as claimed in claim 1 wherein the pro-

portion of carbon compound used is such that substantially two labile halogen atoms are available for each molecule of tetrahydrobipyridyl.

16. A process as claimed in claim 1 wherein the interaction is carried out at a temperature in the range -55° C. to 70° C. 5

17. A process as claimed in claim 1 wherein the interaction is carried out at a temperature in the range of 0° C. to 50° C.

18. A process as claimed in claim 1 wherein the bi- 10

pyridylium salt is extracted from the reaction mixture by water.
